ATTORNEY

UNITED STATES PATENT OFFICE

VINCENT Z. FELIPE, OF NEW YORK, N. Y.

FOUNTAIN PEN AND PENCIL

Application filed December 20, 1928. Serial No. 227,215.

This invention relates to writing implements and more particularly to types susceptible of being carried about the person, as for instance a fountain pen.

5 For brief notations of a temporary or unimportant nature a fountain pen is often undesirable, it being preferable to use a pencil for many purposes, such marks being readily eradicable and no blotting is required or 10 waiting for ink to dry.

It is therefore an object of the present invention to provide a writing implement in which is contained a complete fountain pen and also, axially of the casing, a pencil so 15 arranged as to be extended into position for use or retracted into the casing.

A further feature is in the provision of 20 means for rendering the pencil or pen each selectively accessible from one and the same end of the casing, thereby obviating the necessity of reversing the implement in order to use the desired point.

Another purpose is to combine with a fountain pen casing a pencil having lead 25 expelling and repelling features and also a supply source for the leads, all being combined in an attractive casing of conventional appearance.

These several important advantages are 30 accomplished by the novel construction and arrangement of parts hereinafter described and illustrated in the accompanying drawings, forming a material part of this disclosure, and in which:—

35 Figure 1 is a longitudinal sectional view taken on the center line of an embodiment of the invention showing the pen point extended.

Figure 2 is a similar view taken in a plane at a right angle to Figure 1 with the pencil 40 point in operative position.

Figure 3 is a partial side elevation of the device, the cap being in section.

Figure 4 is a transverse sectional view taken on line 4—4 of Figure 1.

45 Figure 5 is a similar view taken on line 5—5 of Figure 1.

The device comprises a tubular casing 10 having a cylindrical bore, its outer wall being preferably tapered from a point midway 50 its center to the ends.

Fixed in the front end of the casing is a shouldered sleeve 12, its extending portion being tapered in conformity with the casing, the abutting end of which is provided with a screw thread 13.

55 Slidable within the bore of the sleeve and guided by co-acting keys 14 is a plug 15 having a conical point and containing an axial bore 16 in the inner portion of which are slots 17 to receive and guide keys 18 set in collar 19 at the inner end of a pencil holder 20 suited to slide in the bore 16.

The holder 20 is formed conically at its outer portion and contains an opening 60 through which a pencil lead L may extend.

65 The keys 18 limit the outward movement of the holder 20 by contact with the outer ends of the slots 17 and also the retraction of the holder by contact with stop screws 21 set in the sleeve 15 as best seen in Figure 2.

The lead L is moved longitudinally in its 70 holder, in either direction by the means usually employed, as indicated by the coarse screw 22 engaging pins 23 fixed in the lead clamping device commonly used, the lead being adjusted inwardly or outwardly of the holder by rotating the extending end of the holder 20 relative to the collar 19 which is nonrotatable due to the keys 18 and 14.

75 Fixed to the inner end of the screw 22 are 80 a pair of opposed bars 24 extending from a nut 25 threaded upon a screw 26R of right hand pitch, the same having a section 26L of left hand pitch of corresponding length.

The outer end 27 of the screw section 26L 85 is rectangular and provided with a thread at its end to engage a nut 28 set in an axial recess formed in the outer surface of a plug 29 constituting the end of the casing.

An annular recess 30 in the periphery of 90 the plug is suited to receive pins 31 fixed in the casing near its end permitting rotation of the plug but preventing relative end movement.

In the outer end of the plug 29, adjacent 95 its periphery are a series of indentations 32 adapted to receive the corresponding ends of sheath 33 having open containers 34 to receive and hold extra leads, the same being retained by a screw 35 having a flanged head 100

36 knurled to provide an effective finger grip.

The screw 35 is threaded into the outer end of a cap 37 into the adjacent end of which the sheaths 33 and their hollow cylindrical connections 38 are firmly secured.

The opposite end of the cap is interiorly threaded, as at 13', to engage the threads 13 of the casing or barrel when disposed over its opposite end, as shown in Figure 3.

10 From the foregoing it will be seen that the pencil holding elements, including the holder 20 and plug 15 may be moved longitudinally with respect to the casing 10 by applying the cap 37, causing engagement of the sheath 15 ends with their sockets 32 and rotating the cap relative to the casing, thereby turning the screw 26R to move the nut 25, whereby the lead L is projected for use or retracted as may be desired.

20 It will also be apparent that the screw 26L is also rotated with the section 26R, by means of which the pen point P is extended or retracted and in opposed relation to the pencil L.

25 This is accomplished by reason of a nut 40 threaded on the screw section 26L, the nut bearing against the bore of the casing at one end and having affixed at its opposite end a bar 41 of concave cross section, this bar terminating at its opposite end in a ferrule 42 in which one end of an ink sac 43 is fixed.

30 The nut 40 has an extension slotted at its end to engage a key 11 fixed in the bore of the casing, and extending between the plugs 35 15 and 29 as seen in Figures 1 and 5, the nut thus being prevented from turning with the screw 26L.

Also fixed to the nut 40 is the re-entrantly turned end of a spring pressure bar 44, its 40 outer end extending almost to the ferrule 42 and being arranged to partially enclose the sac 43, opposite the bar 41.

45 The spring bar 44 is adapted to receive the thrust of the usual lever 45, when filling the sac with ink, transmitting pressure to it upon raising the outer extending end of the lever, which is maintained normally within a recess in the outer side of the casing by the effect of the bar 44.

50 Fixed in the outer end of the ferrule 42 is a tube 46 having an ink conveying duct 47, the tube 46 being expanded as at 46' and shaped to act as a holder for the pen nib P.

The plug 15 is flattened and grooved, as at 55 48 along one side to permit the sliding passage of the tube stem 46', this element being limited in its longitudinal movement by a key 49 slidable in a groove 50 formed in the inner wall of the sleeve 12, as best seen in Figure 1.

60 It will now be apparent that either the pencil or pen may be projected into operative position by rotating the cap 37 when placed on the end of the casing opposite the points.

65 It will be equally clear that either the pen or pencil may be used without possible inter-

ference with each other, and when either are extended to the limit, as well as retracted, that the cap placed thereover and secured by the threads affords perfect protection for the points.

Both the pen and pencil are operatively positioned in the usual manner; the pen is provided with the usual filling means and the pencil with a lead adjusting device of approved type, the whole constituting an efficient and neat appearing writing implement.

As changes of construction could be made within the scope of the invention, it is intended that all matter contained in the foregoing description or shown in the accompanying drawings shall be interpreted as illustrative and not in a limiting sense.

Having thus described the invention, what is claimed as new and desired to secure by Letters Patent, is:—

1. A writing implement containing two points of unlike character slidable therein, a screw having right and left hand threaded sections of uniform pitch throughout their lengths, a nonrotatable nut on each section connected with each point independently, and means for rotating said screw.

2. A writing implement comprising a casing having an axial pencil point and an offset pen point, a screw having right and left hand sections, a nut on each section, connections between each nut and the respective points, a plug rotatable in the end of said casing opposite the points said plug being rigidly attached to the screw, a cap disposable either over said points or over said plug, and means in said cap engageable with said plug whereby to transmit rotary motion.

3. A writing implement comprising a casing having two apertures in its end and containing a pen and pencil, and means rotatably mounted on the opposite end of said casing to extend and retract the pen and pencil selectively through the mentioned apertures.

4. A writing implement comprising a casing containing an axial opening and a second opening adjacent thereto in its end wall, said casing having a pen and pencil therein, and rotatable means at the opposite end of said casing to coincidently move either pen or pencil outwardly or inwardly in opposed relation through the mentioned openings.

5. A writing implement comprising a casing having an axial opening and a passage adjacently parallel thereto, a plug slidably mounted in one end thereof, said plug having an axial bore, a second plug rotatable in the opposite end, a cap, means in said cap to operatively engage the second plug when the cap is on the opposite end of the casing, a right and left hand screw actuated by the second plug, a pencil holder slidable through the bore of the first plug, connections between the two plugs.

said screw and the first plug upon rotation of the second plug, a pen slidable in the passage, and connections between said screw and said pen, said connections moving in opposite directions upon rotating said screw.

5 In testimony whereof I affix my signature.

VINCENT Z. FELIPE.
